UNITED STATES PATENT OFFICE.

GEORGE B. ALLISON, OF LOS ANGELES, CALIFORNIA.

ROTARY FAN.

1,356,508.

Specification of Letters Patent.

Patented Oct. 26, 1920.

Application filed December 10, 1917. Serial No. 206,398.

To all whom it may concern:

Be it known that I, GEORGE B. ALLISON, a citizen of the United States, residing at the city of Los Angeles, State of California, 5 have invented new and useful Improvements in Rotary Fans, of which the following is a specification.

It is the object of my invention to produce a rotary fan of simple construction 10 and great efficiency.

In the drawings forming a part of this application—

Figure 1 is a front elevation of my improved fan.

15 Fig. 2 is a side elevation of what I term a two unit fan with parts in section and parts in elevation.

Fig. 3 is a plan in projection of the fan blades and hub, the fan shell being removed 20 for clearness of illustration.

Referring to the drawings—5 is the casting or outer shell of my fan which is tubular in general outline. To the central portion thereof is secured an outlet or inlet 25 tube 6 of smaller dimensions than the shell. To the ends of the outer shell are secured bearing arms 7 and 8 in which is revolvably mounted fan shaft 9 which carries on the end thereof pulley 10 to which power is applied to rotate the shaft. To shaft 9 at the 30 ends of shell 5, if of double unit construction, are secured rotary fans composed of hubs 11 and blades 12. As shown diagrammatically in Fig. 3 the ends of the blades 35 project at an angle to the plane of the revolution of the fan and the central portions travel in the plane of the revolution of the fan, but in a two unit fan the angles of the fan blades at one end are the reverse of the 40 angle at the other end. An outer shell 14 is secured to the outer edges of the fan blades.

When the fan is constructed as a double unit fan the shell is divided by a Y-shaped partition 13 the upper portions of which 45 are curved as shown in Fig. 2. This partition deflects the air drawn into the shell into the outlet tube from which it passes to the place of use when the fan is used to drive air into a mine or other place of use. By 50 reversing the direction of travel of the fan blades, the fan is equally powerful in sucking air out of a mine or other places from which it is desired to remove the air.

From the foregoing description it will be 55 seen that a two unit fan can be constructed

for a sum only slightly more than a one unit fan and will have double the capacity of a one unit fan. It will also be observed that the hub of the fan prevents any air escaping through the center of the blades and thus aids in causing the air sucked in by the 60 blades to pass through the outlet tube; when a single unit fan is used the shell would be elbow shaped. In the drawings I have shown the ends of the blades set at an 65 angle of about 60 degrees to their plane of rotation as I prefer that angle for high speed, but the angle can be varied to suit the work to be done. I have also shown the central portions of the fan blades in the 70 plane of rotation but if desired the blades could be straight but on an angle to the plane of rotation. By placing a shell on the outer ends of the fan blades the friction of the air on the outer shell is eliminated and 75 it takes less power to rotate the fan. This shell is substantially as wide as the blades and braces the ends thereof and connects them together so that the outer ends at all points travel at the same rate of speed 80 and without vibration.

Having described my invention, I claim:

1. A rotary fan comprising an outer shell; bearing arms secured to said shell; a shaft mounted in the bearing arms and 85 shell; and a fan having a large central hub mounted on said shaft, the blades of said fan being secured to the hub and having the ends set angularly to the plane of revolution and the central portion set in the plane 90 of revolution of the blades and a shell secured to the outer ends of the blades and revoluble therewith.

2. A rotary fan comprising a tubular shell; bearing arms secured to said shell at 95 the ends thereof; a shaft mounted in said arms; fans having large hubs secured to said shaft adjacent to said arms, said fans having blades whose ends project at an angle to the plane of their revolution and the 100 central portions lie in the plane of their revolution, the angles at one end being reversed as to those of the other end; an outlet tube secured to said shell, and a Y-shaped partition in said shell, said partition terminating centrally of said outlet tube. 105

In witness that I claim the foregoing I have hereunto subscribed my name this 3rd day of December, 1917.

GEO. B. ALLISON.
